POLE PLANING MACHINE

James D. Taylor and Wallace E. Jones, Spartanburg, S. C., assignors to Taylor-Colquitt Co., Spartanburg, S. C., a corporation of South Carolina

Application May 6, 1938, Serial No. 206,470

7 Claims. (Cl. 144—114)

The present invention relates to machines for operating on lumber and refers particularly to a machine for effecting a cutting or planing operation on poles or logs.

5 An object of the invention is the provision of a machine designed to plane off a predetermined portion of a pole to form a flattened section capable of receiving cross arms or the like.

10 A further object is to provide a machine having an open frame through which a pole can be fed and which is adapted to receive and hold a pole supporting truck against further forward movement while the pole is being operated on by the machine.

15 Another object is the provision of a pole planing machine adapted to receive a pole, plane off a predetermined length of the pole, and then permit the pole to be withdrawn from the same side of the machine from which it was fed.

20 A further object is to provide a cutting or planing element suspended from the frame of the machine and capable of movement into and out of operative cutting position. Means are also provided to adjust the cutter to accommodate poles 25 of different diameters.

Another object is the provision of means associated with the cutter adjustment to permit upward movement of the cutter element during the planing operation, in the event of an extreme upward thrust, thereby preventing damage to the cutter.

30 A further object is to provide a pair of log supporting trucks for feeding a pole to the machine and then withdrawing it after the machine has completed the planing operation.

35 A still further object is the provision of a truck adapted to support the front of a pole and to be moved into the frame by the pole. This truck is provided with means for preventing movement 40 of the pole relative to the truck until the truck is positioned within the machine under the cutter element. At this point the pole retaining means will be rendered automatically inoperative to permit the pole to move forwardly on the truck underneatn the cutter element.

45 Another object is to provide a rear truck adapted to support the rear end of a pole and lock it against both rotary and longitudinal movement on the truck.

50 With the foregoing and other objects in view the invention will now be more fully described, reference being had to the accompanying drawings, in which,

55 Figure 1 is a top plan view of the machine with

the pole supporting trucks in operative position to feed a pole under the cutter element.

Figure 2 is a side elevation of the machine showing the truck supporting a pole in position to be operated on.

Figure 3 is a perspective view of the pole after it has been operated on by the machine.

Figure 4 is a horizontal section through the machine on line 4—4 of Figure 2.

Figure 5 is a horizontal section on line 5—5 of 10 Figure 2.

Figure 6 is an enlarged front view partly in section of the cutter element and the means for moving it into and out of operative position in the machine.

Figure 7 is a vertical section through the cutter element showing the latter in inoperative position.

Figure 8 is a view similar to Figure 7 showing the cutter element in operative position.

Figure 9 is a longitudinal vertical section 20 through the front pole supporting truck.

Figure 10 is a section through the truck taken along line 10—10 of Figure 9.

Figure 11 is a longitudinal vertical section 25 through the rear pole supporting truck, and

Figure 12 is a section taken on line 12—12 of Figure 11.

Referring now to Figures 1 to 3 of the drawings, the numeral 10 designates generally the pole cutting or planing machine forming the subject matter of the present invention. This machine comprises a frame structure of substantially open formation, in the top portion of which is mounted a cutter or planing element 11. A pair of front and rear log supporting trucks 12 and 13 are movable on tracks 14 and are adapted to support a pole 15 in position to be moved under the planing element 11, as clearly shown in Figure 2.

Means are provided (to be later described in detail) for clamping or locking the log 15 to the rear truck 13 to prevent rotary or longitudinal movement of the log relative to the rear truck. The front truck 12 is also provided with means for engaging the front end of the pole and preventing forward movement thereof relative to the front truck as the pole is moved into position beneath the planing element 11. However, before the pole actually comes into contact with the cutter element, means are provided to automatically release the pole engaging element and permit the pole to 40 be moved forwardly on the front truck under the cutter element while the front truck is confined within the frame of the machine. The pole is advanced under the cutter element by moving the rear truck forwardly and this movement will 45

25

30

35

40

45

50

55

be transmitted by the pole to the front truck until the latter is held against further movement by the frame of the machine. Thereafter, the rear truck is moved forwardly until the desired cutting or 5 planing operation has been accomplished, whereupon the cutter element is raised to its upper inoperative position and the pole withdrawn from the machine. The feeding of the pole into the machine and the subsequent withdrawal thereof 10 may be performed in any suitable manner, that is, this may be a manual operation or means may be employed for automatically feeding and withdrawing the pole from the machine. Means are provided to adjust the cutter element to accommodate poles of different diameters and to make 15 different depths of cut. The machine is particularly adapted for planing or flattening one section of a log or pole to accommodate cross arms or the like (see Figure 3), but is useful in many other 20 planing operations.

Referring to Figures 4 to 7, the cutter or planing element 11, together with its adjusting mechanism, will now be described in detail. This element comprises a cylindrical cutter head or blade holder 16 in which are mounted a plurality of cutters or blades 17. The holder 16 is fixed to a shaft 18 rotatably mounted in bearings carried by bearing housings 18' mounted in the side plates 19 of a casing 20. This casing substantially encloses 25 the cutter element but is open on its lower side, as clearly shown in Figures 6, 7 and 8. The casing 20 is pivotally connected to a pair of spaced supporting plates 21 by means of two sets of spaced arms 22. Each arm has one end thereof pivotally connected to one of the plates 21 and one end 30 pivotally secured to the casing 20 and is mounted in parallel relation to its companion arm. Furthermore, each arm is mounted in alignment with the corresponding arm of the other set, whereby 35 the casing and blade cutters may be raised and lowered into an operative position without changing the relative position of the casing with respect to the blades. That is, the casing will always 40 remain in the correct position to receive a pole regardless of the movement of the casing on the arms 22. Thus, the cutting element will always 45 be in the correct position for receiving and operating on a pole regardless of the position to which the cutter has been adjusted.

50 The supporting plates 21 are suitably secured to a pair of horizontal beams 23 mounted between upright I-beams 24 in the top portion of the machine. The vertical I-beams 24 cooperate with horizontal beams 25 to form an open supporting frame which, as described above, permits the front pole supporting truck to be moved into the frame and also allows a pole to pass into and through the frame during the planing operation.

Referring again to Figures 5 and 6, it will be 60 observed that while one end of the shaft 18 is journalled in one of the housings 18', the other end of the shaft passes through its respective housing and side plate 19 and has a pulley 26 secured to its extreme end. This pulley is operatively connected to a motor pulley 27 by suitable belting 28. Pulley 27 is mounted on a shaft 28' 65 of an electric motor 29 suspended from horizontal plates 30 suitably supported in the frame structure of the machine. Operation of the motor 29 will 70 rotate the blade holder 16 at the desired speed. It will be observed that the arms 22 are formed of overlapping sections 31 and 32 adjustably secured together by fastening elements 33 passing through slots in the sections 31 and 32. This 75 arrangement permits any slack in the pulley belts

28 to be taken up so that the motor will drive the holder 16 at the desired speed.

It is necessary that means be provided to quickly move the cutter element 11 into and out of operative cutting position and also to adjust the cutter head to accommodate poles of different diameters. The means for accomplishing this comprises (see Figures 6 to 8) a rod 34 having one end thereof secured to a cross rod 35 which is pivotally mounted between ears 36 projecting upwardly 10 from the casing 20. Rod 34 is threaded throughout a substantial portion of its length and passes through threaded openings in a sleeve 37. The upper end of this sleeve is fixed to a cross arm 38 having operating handles 39 secured to opposite 15 ends to permit rotation of the sleeve 37 on the rod 34 and thus adjust the rod and cutter element vertically to take care of poles of various sizes.

The arm 38 normally rests upon the top of a collar 40, which collar also encloses the sleeve 37 20 and permits sliding movement of the sleeve within the collar. The collar 40 is pivotally connected to and supported between spaced plates 41 by means of threaded bolts 42 passing through aligned openings in these elements. Each plate 41 (see 25 Figures 7 and 8) is preferably of triangular shape and is connected to the other plate by a cross bar 43. The plates 41 and cross bar 43 constitute the crank portion of a crank shaft 44 which is suitably journalled in bearings 45 mounted on the 30 top of the frame structure of the machine. An operating lever 46 is connected to one end of the crank shaft 44 and is adapted to rotate the crank shaft to raise the cutter element 11 from its operative position (see Figure 8) to its inoperative 35 position (see Figure 7).

It will be observed that when the cutter element is in its operative position, the collar 40 is supported by the plates 41 in a position forwardly of the cross bar 43 and the axis of the crank shaft 44. Furthermore, the cross bar 43 is in vertical alignment with the axis of the crank shaft. The plates 41 in this position are supported upon the bifurcated plate 47 and this in conjunction with the arms 22 adequately support the cutter in position to receive and operate upon the poles as they are fed to the machine. However, the cutter head 16 and its casing 20 are capable of upward movement by reason of the slidable engagement of the sleeve 37 and collar 40. Thus, if an unusual upward thrust is exerted upon the cutter element by the pole, the cutter element will be raised and will thus be protected from injury by any undue force exerted from below.

When the pole has been operated on to the desired extent, the cutter element may be easily and quickly raised to its inoperative position by moving the lever 46 rearwardly. This operates the crank shaft 44 and moves the plates 41 from the position shown in Figure 8 to that shown in Figure 7. This will have the effect of raising the rod 34 and moving the upper portion thereof to a point in rear of the axis of the crank shaft or past dead center. Furthermore, this movement 65 of the plates will also carry the cross rod 43 to a point in rear of and below the axis of the crank shaft. This rod constitutes means for limiting the rearward movement of the collar 40. Thus, in the position shown in Figure 7, the cutter element is not only moved to its inoperative position but by reason of the association of the crank shaft elements and the collar 40, the cutter element will be locked and retained in its inoperative position until the lever 46 is again actuated 70

to rotate the crank shaft and lower the cutter element to its operative position.

Referring to Figures 5 to 7, a bar 48 is adjustably mounted on and extends across the front of the casing 19 and is adapted to directly contact and rest upon a pole as it is fed into the machine. This bar may be of any suitable construction and by loosening the fastening elements 49, it may be adjusted vertically with respect to the casing and thereby adjust the blades 17 for different depths of cut, as desired. The casing 19 is also provided with a relatively flat elongated extension 50 which surrounds an opening in the casing. This extension 50 forms a discharge spout for permitting escape of chips which are carried into the casing by the rapidly rotating blades 17. At a point below the extension 50, the casing supports an inclined guide plate 51 which is adapted to engage the end of a pole as it is fed into the machine and to slightly raise the casing and cutter element so that the latter is in correct cutting position as it engages the end of the pole. It will be observed that the lower end of the cross bar 48 is normally positioned below the lowest point of the guide plate 51 so that during the actual planing or cutting operation, the bar 48 will be in contact with the top of the pole instead of the guide plate 51.

Referring to Figures 2, 4 and 5, it will be observed that a horizontal cross beam 52 extends across and is secured to the lower portions of the forward uprights 24 of the frame of the machine. This cross beam is directly in the path of the forward truck 12 and is adapted to engage the truck and hold it within the frame after the forward end of the pole to be operated on, has passed under the cutter element 11. Adjustably secured to the top of the cross beam 52 is a bar 53 which extends rearwardly within the frame for a purpose to be presently described. This plate is provided with a plurality of spaced openings 54 which permit adjustment of the bar on the beam. A suitable fastening element 55 is utilized to secure the bar 53 in operative position.

Referring to Figures 2, 4, 9 and 10, the forward truck 12 will now be described in detail. This truck comprises a pair of longitudinally extending frame members 56 in which are journaled and housed the truck wheels 57. A pair of cross beams 58 connect the frame members 56 and support a longitudinally extending I-beam 59. On top of the I-beam and centrally thereof is mounted a substantially Y-shaped roller support 60 which carries the stub shafts 61 upon which rollers 62 are freely rotatable. It will be observed that the rollers are inclined inwardly and downwardly and cooperate to form a pole support and guide for initially supporting the front end of a pole and then guiding the remainder of the pole in proper relation to the cutter element 11 as the pole is fed into the machine. Upon the front end of the I-beam 59 is mounted a sleeve 63 which receives and guides a vertically slideable plunger 64. The lower end of this plunger is connected by linkage 65 to a cross shaft 66 which extends between and is journaled in plates 67 secured to the inner faces of the frame members 56. A pair of levers 68 and 69 are rigidly connected to opposite ends of the shaft 66 and a stop element 70 is carried by and projects inwardly from one of the frame members 56 to engage the lever 68 and limit the forward movement of the levers. It will be observed (see Figure 4) that the lever 69

is in alignment with the bar 53 so that ultimately the lever will contact the rear end of the bar and be moved rearwardly by the bar.

When the levers 68 and 69 are in their forward position, the plunger 64 will be raised to its highest position, with the extreme upper end of the plunger located above the level of the inner ends of the rollers 62. The plunger is centrally positioned with respect to the rollers and is adapted to contact the front end of a pole and prevent forward movement thereof relative to the truck when the plunger is in its raised position (see Figure 2). As the pole and truck 12 are moved forwardly, the front end of the pole will remain in contact with the plunger until the lever 69 engages the rear end of the bar 53. When this occurs, further forward movement of truck 12 will effect a rearward movement of the lever 68 and this will rotate the shaft 66 and move the plunger downwardly in its sleeve 63 whereby the upper extremity of the plunger will be clear of the pole. Thereafter, the pole will be free to slide forwardly on the rollers 62 and since the truck 12 will engage the cross beam 52 immediately after the plunger 64 is lowered, the truck will be confined in the machine and adequately support the pole as it is fed under the cutter element through the frame.

Referring to Figures 1, 2, 11 and 12, the rear truck 13 will now be described in detail. This truck, similar to truck 12, is provided with spaced longitudinally extending frame members 71 in which are journaled wheels 72. These members are connected by cross beams 73 and a cross frame 74 extends between and is mounted on top of the frame members 71. A pair of spaced pole supporting wheels or rollers 75 are loosely mounted on shafts 75' which are supported in the cross frame 74 and project forwardly of the cross frame 74 and loosely support arms 76 and 77 respectively. A flexible chain 78 has one end thereof secured to the arm 76 adjacent its inner end, while the free end of the chain is adapted to be detachably connected to the arm 77 (see Figure 12) when a log is to be clamped to the truck 13. The outer extremity of the arm 76 is provided with a recess 79 which receives one end of a coil spring 80, the other end of the spring being secured to one of the frame members 71.

It will be observed that the arm 77 is mounted on its shaft intermediate the ends of the arm and is provided with a stop pin 81 positioned between the inner end of the arm and the axis of the shaft 75'. Furthermore, a hook or latch 82 is pivoted to the arm on the other side of the shaft from the pin 81 and in close proximity to the shaft. Assuming now that a pole has been placed on the trucks 12 and 13, the chain 78 is wrapped around the rear end of the pole (see Figures 2 and 12) and the latch 82 is connected to one of the end links of the chain. When the slack has been taken in the chain but before any pressure has been exerted on either of the arms 76 and 77, they will assume their full line positions illustrated in Figure 12. Thereafter the arm 77 is rotated to its dotted line position which will move the arm 76 against the tension of the spring, to its dotted line position. As the arm 77 is moved from its full line to its dotted line position, the chain 78 will be tightened about the pole so that it will be retained against longitudinal movement with respect to truck 13. When the free end of the arm 77 passes the axis of the shaft 75', the arm, latch 82 and end of the chain will be past dead 70 75

center and this will have the effect of locking the arm against outward of counterclockwise movement. In fact after the free end of the arm 17 has moved past the vertical axis of the shaft, 5 it will be urged inwardly until the pin 81 abuts the chain. Thereafter the arm will be locked in this position until it is desired to release the chain from the pole.

In addition to clamping the pole on the truck 10 by means of the chain 78, a further locking means is employed which cooperates with the chain to lock the pole on truck 13 against both longitudinal and rotary movement with respect to the truck. This means comprises a drift pin 83 15 slidably mounted in a sleeve 84 secured to the cross frame 74. The drift pin is provided with a sharpened point 85 and its lower end is connected by linkage 86 to a cross shaft 87 journalled in the frame members 71. A pair of levers 88 are connected to the ends of the shaft 87 exteriorly of the frame members 71 and are adapted to rotate the shaft 87 and thereby move the drift pin 83 vertically in its sleeve 84. After the chain 10 has been tightened about the pole and the 20 arm 17 locked in operative position, one or both of the levers 88 is moved downwardly with sufficient force to cause the point 85 of the drift pin to penetrate the pole (see Figures 11 and 12). This will effect an upward thrust of the drift 25 pin against the pole and chain 78 so that the drift pin cooperates with the chain to adequately 30 clamp or lock the pole on the truck 13.

With one end of the pole clamped to the truck 13 as above described and its front end supported 35 on the truck 12, it is ready for movement into the frame of the planing machine. Any desired type of power is then applied to either the rear end of the pole or the truck 13, which also causes forward movement of the truck 12. The front end of the pole and truck 12 will thus be moved into the frame where continued movement will effect operation of the lever 69, thus lowering the plunger 64 and permitting the pole to pass into engagement with the cutter element. 40 The rear truck 13 will be moved forwardly until it comes into contact with truck 12 or until a predetermined length of the pole has been planed or operated on. When the desired cut has been taken, an operator will actuate the lever 46, raising 45 the cutter element 11 into its inoperative position, whereby the pole is free to be withdrawn from the machine. As stated above, both the feeding and withdrawal operations may be 50 manual and, if desired, a cable or similar element (not shown) may connect the trucks 12 and 13, whereby withdrawal of truck 13 will remove truck 12 from the open frame of the machine. However, any mechanical means (not 55 shown) may be employed to automatically feed the pole 15 and trucks 12 and 13 into the machine and withdraw the same after the desired planing or cutting action has been performed.

It is to be understood that while the machine 60 is particularly adapted for planing or providing flattened surfaces on poles, as shown in Figures 2 and 3, the present invention is capable of performing many different operations on poles or other lumber and is not limited to the specific 65 functions shown and described. It is to be further understood that the invention is not limited to the details of construction shown in the drawings, and that the phraseology employed in the specification is for the purpose of description 70 and not of limitation.

We claim:

1. A pole supporting truck adapted to feed a pole into the frame of a pole planing machine, a roller guide adapted to directly support and guide a pole, a movable plunger mounted on the truck in advance of and in alignment with the guide and adapted to contact the end of a pole and prevent forward movement of the pole relative to the truck, and plunger operating means carried by the truck and operatively connected to said plunger to move the same out of the path of the pole, said last mentioned means being adapted to be actuated by contact with the frame to release the plunger from the pole to permit the latter to move on the roller guide through 10 the frame of the machine.

2. In a device of the character described, an open frame adapted to receive and house a pole supporting truck, pole planing means mounted in the upper portion of the frame and adapted to operate on a pole as it is moved through the frame, a pole supporting truck, a truck engaging element carried by the frame in the path of the truck to hold the latter in operative position below the pole planing means, and means carried by said truck and adapted to be positioned in the frame below the pole planing means to guide and center a pole under the planing means as it is fed through the frame, said truck engaging element being at a lower level than said last 30 mentioned means and out of the path of the pole.

3. In a device of the class described, an open frame adapted to receive and house a pole supporting truck, pole planing means mounted in the upper portion of the frame and adapted to operate on a pole as it is moved through the frame, a pole supporting truck, a truck engaging element carried by the frame in the path of the truck to hold the latter in operative position below the pole 40 planing means, while permitting movement of the pole through the frame, means carried by said truck and adapted to be positioned in the frame below the pole planing means to guide and center a pole under the planing means as it is fed 45 through the frame, means carried by the truck in advance of the centering means for preventing forward longitudinal movement of a pole relative to the truck, and means carried by the frame and engageable with said last mentioned means to 50 render the same inoperative and thereby permit movement of a pole through the frame past the planing means.

4. In a device of the character described, an open frame adapted to receive and house a pole 55 supporting truck while a pole is being fed on the truck through the frame for planing, said frame including spaced side members for receiving and housing the truck during the pole planing operation, means mounted on the frame between the side members and in the path of the truck to prevent further forward movement of the truck and to correctly position the truck in pole planing position, and means mounted on said frame in advance of said last mentioned means and adapted 60 to actuate a pole releasing elements of the truck before the truck contacts said first mentioned means.

5. In a device of the class described, an open frame adapted to receive and house a pole supporting truck, pole planing means mounted in the upper portion of the frame and adapted to operate on a pole as it is moved through the frame, a pole supporting truck, a truck engaging element carried by the frame in the path of the truck to hold 70

75 the latter to move on the roller guide through the frame of the machine.

the latter in operative position below the pole planing means, while permitting movement of the pole through the frame, and a pair of oppositely inclined pole supporting rollers mounted on the 5 truck and adapted to be positioned in the frame directly below the pole planing means when the truck is in contact with the truck engaging element of the frame, whereby to guide and center a pole under the planing means as it is fed 10 through the frame.

6. In combination, an open frame adapted to receive and house a pole supporting truck while a pole is being fed on the truck through the frame, a pole supporting truck adapted to carry a pole 15 into the frame under a planing element, truck engaging means mounted on the frame in the path of the truck and adapted to prevent further forward movement of the truck in the frame, pole engaging means mounted on the truck and 20 adapted to contact an end of a pole and prevent

forward movement of the pole on the truck, and means carried by said truck and operatively connected to said pole engaging means to move the latter into and out of contact with the end of a pole.

7. A pole supporting truck adapted to feed a pole into the frame of a pole planing machine, means carried by the truck for supporting and centering a pole as it is fed through the pole planing machine, a member movably mounted on the 10 truck in advance of and in alignment with the pole supporting and centering means and adapted to contact the end of the pole and prevent forward movement of the pole relative to the truck, and member operating means mounted on the 15 truck and operatively connected to the member to move the latter into and out of pole engaging position.

JAMES D. TAYLOR.
WALLACE E. JONES. 20
